(57) **CLAIM**

The ornamental design for a fighting chair, as shown and described.

DESCRIPTION

FIG. 1 is a front perspective view of a fighting chair according to one embodiment.

FIG. 2 is a front view of the fighting chair of FIG. 1.

FIG. 3 is a back view of the fighting chair of FIG. 1.

FIG. 4 is a first side view of the fighting chair of FIG. 1.

FIG. 5 is a second side view of the fighting chair of FIG. 1.

FIG. 6 is a top view of the fighting chair of FIG. 1.

FIG. 7 is a bottom view of the fighting chair of FIG. 1; and, FIG. 8 is a perspective view of the fighting chair of FIG. 1 attached to a boat.

The broken lines shown in the drawings are included for the purpose of illustrating environmental structure and portions of the fighting chair that form no part of the claimed design.
